UNITED STATES PATENT OFFICE

LAURENCE E. TOPHAM, OF WENHAM, MASSACHUSETTS, ASSIGNOR TO UNITED SHOE MACHINERY CORPORATION, OF PATERSON, NEW JERSEY, A CORPORATION OF NEW JERSEY

MACHINE FOR OPERATING UPON LASTS

Application filed August 20, 1930. Serial No. 476,579.

This invention relates to machines for operating on lasts. The invention is herein illustrated as embodied in a machine for disassembling the parts of separable lasts of the type in the use of which a forepart and a heel part are held together in assembled relation within a shoe by means comprising interengaging bonding devices and a latch, the latch being releasable from within the jack pin thimble hole of the heel part of the last, and the bonding devices being disengageable after release of the latch to disconnect the last parts and to effect separation or disassembly of those parts by relative tilting and sliding movements thereof so that the last may subsequently be removed from the shoe. A last of this general type is described and claimed in a co-pending application, Serial No. 386,034, filed August 15, 1929, in the name of G. P. S. Cross, the last disclosed in that application being characterized by having a latch which is shaped like a hook and which is mounted for tilting movement in directions heightwise of the last between engaging and disengaging positions.

One object of the present invention is to provide a machine which will be especially adapted for disassembling the foreparts and heel parts of separable lasts of the type disclosed in the application above referred to, although in various aspects the invention is not limited to machines for use in connection with that particular type of last.

With this object in view, one feature of the present invention consists in the provision, in a machine for disassembling the foreparts and heel parts of separable lasts of the type having interengaging bonding elements and means for locking the bonding elements in interengaged relation, of relatively movable members for rigidly holding one of the last parts and for releasing the locking means, and means for thereafter relatively moving the last parts to disengage the bonding elements. In the illustrated machine, a jack pin is movable heightwise of the last to co-operate with a fixed abutment to clamp the heel part of the last and to release a latch to unlock the bonding elements of the last. Also, as herein illustrated, the means for relatively

moving the last parts is operated first to tilt the forepart of the last to disengage one set of bonding elements and thereafter to slide the last forepart while maintaining it in tilted position to disengage the other set of bonding elements. Thus there is provided a machine for disassembling the foreparts and heel parts of separable lasts having means for rigidly holding the heel part of such a last, and means for moving the forepart of the last relatively to the heel part to disengage the bonding elements of the last, such an organization constituting a further feature of the present invention.

The invention further consists in various features of construction and combinations and arrangements of parts hereinafter described and claimed.

In the accompanying drawings, Fig. 1 is a perspective view of the machine embodying the features of the present invention;

Fig. 2 is a view, partially in front elevation and partially in section, and on an enlarged scale, of the head of the machine shown in Fig. 1;

Fig. 3 is a detailed elevational view of a portion of the mechanism shown in Fig. 2;

Fig. 4 is a plan view of the machine;

Figs. 5 and 6 are detailed plan views of the jack pin and associated mechanism;

Fig. 7 is a side elevational view, partially broken away, of the head of the machine;

Figs. 8 and 9 are detailed sectional views on an enlarged scale of parts of the machine shown in Fig. 7;

Fig. 10 is a view, partially in elevation and partially in section, of a separable last having a shoe mounted thereon and illustrating the mode of operation of the machine upon the last; and

Fig. 11 is a view similar to Fig. 10 but illustrating a further step in the operation of the machine.

The machine shown in the drawings is designed to operate upon a separable last A which is shown in detail in Figs. 2, 10 and 11 and which is substantially like the last disclosed in the co-pending application Serial No. 386,034, hereinbefore mentioned. Brief

ly described with reference to the figures above specified, the last A comprises a forepart B and a heel part C which are adapted to be firmly secured together while the last is in use and to be entirely separated one from the other to facilitate the insertion of the last in a shoe or the removal of the last from a shoe. The means for securing together the forepart and the heel part of the illustrated last comprise a hook latch D and two sets of bonding elements, one set being indicated at E and the other set at F. The bonding elements E are adapted to be engaged and disengaged by relative heightwise sliding movement of the last parts B and C. When the last parts are assembled, however, relative sliding movement thereof for the purpose of disengaging the bonding elements E is resisted by the interengagement of the other set of bonding elements F and the elements F can be disengaged only by relative tilting or rotational movement of the last parts about a transverse horizontal axis. The latch D, however, normally prevents such relative tilting of the last parts and thus serves to lock the bonding elements in interengaged relation. To disassemble the last parts, therefore, the latch D must first be tripped and thereafter the last parts must be first relatively tilted about a transverse horizontal axis and thereafter relatively slid in a direction heightwise of the last. The latch D is hooked or notched at G to engage and lock together two plates H and I which are fixed to the forepart B and the heel part C, respectively, of the last and which carry the bonding elements E and F. The latch D is adapted to be tripped by a rocking or tipping movement and a tail J on the latch projects into a thimble hole K in the heel part of the last so that a properly shaped tool or jack pin can press against the tail J, and thus trip the latch D so as to release the plates H and I preparatory to disassembly of the last parts. For a more detailed description of the construction of a separable last of the type herein shown and for a more thorough understanding of the manner of assembling and disassembling the parts of the last, reference may be had to the co-pending application Serial No. 386,034 hereinbefore mentioned.

The illustrated machine is designed to operate upon a separable last of the type briefly described above, while the last parts are assembled and secured together within a shoe, to trip the latch D and to disengage both sets of bonding elements of the last so that the last parts may be readily removed from the shoe. For this purpose the illustrated machine comprises a vertically movable jack pin 14 which functions to support a last which is to be operated upon and to trip the latch preparatory to disengagement of the bonding elements, a fixed abutment 16 for engaging the heel of a shoe on the last, a downward-

ly movable abutment or shoe-bottom-engaging pad 18 for tilting the forepart of the last to disengage the bonding elements F, and an upwardly movable post 20 which is engageable with the cone of the last for sliding the last forepart upwardly to effect disengagement of the bonding elements E.

The above-mentioned parts are supported by a frame comprising a casing 22 which surrounds a hollow pedestal 24. The fixed abutment 16 consists of a jaw formed at the upper extremity of a bracket 26 which is bolted to one side of the casing 22, the abutment jaw 16 having a horizontal lower surface for engaging the tread surface of the heel of a shoe, such as the shoe X shown in the drawings, on the last which is to be operated upon. The jack pin 14 is raised to move the heel of the shoe into engagement with the abutment 16 and also to move the sole of the shoe into engagement with the abutment or pad 18 by mechanism actuated by a foot treadle 30 (Fig. 1) which is pivoted at 32 to the base of the pedestal 24. The treadle 30 also actuates mechanism for moving the pad 18 to tilt the forepart of the last in the shoe X and to raise the post 20 to slide the forepart of the last upwardly relatively to the heel part.

The jack pin 14 is provided with a laterally projecting lug 34 the upper end of which is constructed and arranged to engage the tail of the latch D in the last and upon upward movement of the jack pin to trip the latch so as to permit the above-described tilting and sliding movements of the last forepart to take place. At its lower end the jack pin 14 is pivoted at 36 to a post 38 which is vertically slidable in a bearing 40 formed in a turntable 42 carried by a post 44 which is journaled in the casing 22. The lower portion of the jack pin 14 is reduced in diameter, as indicated at 46, thus providing sufficient clearance between the jack pin and the bearing 40 on the turntable to permit a slight tilting of the jack pin about the pivot 36. This provision for limited tilting movement of the jack pin 14 enables a last on the jack pin to tilt slightly as may be necessary to insure engagement of both the heel and forepart portions of the bottom of a shoe on the last with the abutment 16 and pad 18 respectively and insures engagement of the shoe bottom with the pad 18 irrespective of the size or amount of forepart "spring" in the particular last being operated upon. A spring 48 confined in a socket in the post 38 tends to tilt the jack pin 14 toward the abutment 16. The turntable 42 is countersunk within a recess in the top of the casing 22 and is held in the recess by means of a nut 50 on the lower end of the post 44. A spring 52, secured at one end to the turntable 42 and at the other end to the casing 22, normally holds the turntable in the radial position indicated in Fig. 5, this position being determined by engagement of a pin 51 on

the turntable with one end of a slot 53 in the casing 22. A key 54 fixed to the post 38 and slidable in a keyway 56 in the bearing 40 of the turntable permits vertical sliding movement of the post 38 and the jack pin 14 but prevents axial turning of these parts relatively to the turntable 42. A shoulder 58 is adapted by engagement with the upper end of the key 54 to limit upward movement of the jack pin so as to prevent the jack pin from being accidentally withdrawn from the turntable when a last and shoe is being removed from the machine.

A last, the parts of which are to be assembled, is placed upon the jack pin 14 while the jack pin and the turntable 42 occupy the positions indicated in Fig. 5, the last being positioned at this time as indicated by the dotted lines X' in Fig. 4. Thereafter, the turntable is rotated by manually turning the last and shoe from the dotted line position X' to the full line position X, thus moving the heel of the shoe into position beneath the fixed abutment 16 and the forepart of the shoe into position beneath the movable abutment pad 18 and above the post 20. Upward movement of the jack pin 14 for the purpose of moving the shoe into engagement with the abutment 16 and the pad 18 is effected by means of a push rod 60 which is mounted for vertical sliding movement in a bearing 62 in the casing 22, the jack pin post 38 having been brought into vertical alinement with the push rod 60 by the rotation of the turntable 42 from the position shown in Fig. 5 to the position shown in Figs. 4 and 6.

The means for operating the push rod 60 to raise and lower the jack pin comprises a lever 64 one end of which is pivoted at 66 to the push rod 60 while the opposite end of the lever 64 is forked at 68 to straddle an actuator in the form of a vertical slide rod 70 (Fig. 7) which is mounted in a suitable way 21 in the casing 22. The slide rod 70 is pivotally connected at 72 with the upper end of a treadle rod 74, the lower end of which is pivoted at 76 (Fig. 1) to the treadle 30. The forked end 68 of the lever 64 is located between an adjustable collar 78 on the slide rod 70 and the lower end of a bushing 80 which is normally clutched to the slide rod 70 for vertical movement in unison with the slide rod. The lever 64 is fulcrumed at 82 against the lower extremity of a lug 84 depending from the top of the casing 22, the lever being held yieldingly against the lug 84 by means of two springs 86 secured at their upper ends to the lug 84. This construction permits the lever 64 to rock about the lower end of the lug 84 for the purpose of raising the jack pin to engage the shoe with the abutment 16 and the pad 18, and thereafter, during continued downward movement of the slide rod 70 for purposes

hereinafter to be described, the springs 86 yield, permitting the lever 64 to rock idly about its pivotal connection 66 as a fulcrum.

The means for clutching the bushing 80 to the slide rod 70 comprises a ball 90 (Fig. 8) confined within a hole 92 in the side of the bushing 80 and normally engaging also within a notch 94 in the side of the slide rod 70. Normally, the ball 90 is held seated in the notch 94, thus connecting the bushing 80 with the slide rod 70 so that it is constrained to move downwardly therewith. After the slide rod 70 and the bushing 80 have been moved downwardly a distance sufficient to raise the jack pin 14 the required amount, the ball 90 is brought into a position opposite a notch 96 formed in a fixed bearing sleeve 97 in the casing 22 in which the bushing 80 is slidably mounted. At this time the flanged upper extremity 81 of the bushing 80 engages the casing 22 and further downward movement of the bushing is prevented. Continued downward movement of the slide rod 70 within the bushing 80, however, forces the ball 90 outwardly in the hole 92 into engagement with the notch 96 in the fixed sleeve 97 and out of engagement with the notch 94 in the slide rod, thus releasing the bushing 80 from the slide rod and enabling the slide rod to continue its downward movement without imparting further movement to the lever 64.

When the machine is idle the slide rod 70 is locked against downward movement to prevent accidental starting of the machine by means of a horizontally slidable lock bar 100 (Figs. 4 and 6) mounted in a slideway in the upper portion of the casing 22, the lock bar extending from the slide rod 70 to the turntable 42 and having at one extremity a conical surface 102 adapted to engage a correspondingly shaped socket 104 in the slide rod 70 and at the opposite end a conical surface 106 adapted to engage within a correspondingly shaped socket 108 in the periphery of the turntable 42. When the turntable is occupying the position indicated in Fig. 5 the socket 108 is located out of alinement with the lock bar 100 and the lock bar is maintained at the right-hand limit of its sliding movement, with the conical surface 102 engaged within the socket 104 in the slide rod, thus locking the slide rod against movement. When the last has been moved into the full line position indicated at X in Fig. 4, thus moving the turntable into the position indicated in Fig. 6, the socket 108 in the periphery of the turntable is brought into alinement with the lock bar 100. Thereafter, upon depression of the treadle 30 the conical surface 102 on the lock bar will be forced out of the socket 104 in the slide rod 70 and the slide rod thus released for further downward movement. The movement of the lock bar caused by downward movement of the

70

110

115

120

125

130

treadle and slide rod 70 engages the conical surface 106 on the slide rod with the socket 108 in the turntable, thereby locking the turntable to hold the last in the horizontal angular position indicated by full lines at X in Fig. 5 throughout the operation of the machine. After the last parts have been assembled, however, and the treadle 30 has been released, the resulting upward movement of the slide rod 70 finally returns the socket 104 into alinement with the lock bar and thus unlocks the turntable so that the last may be returned into the dotted line position X' preparatory to removal of the last from the jack pin.

The post 20 is adapted to be raised and lowered through connections with the slide rod 70. The post 20 is raised simultaneously with the raising of the jack pin 14 for the purpose of moving a pad 116 at the upper end of the post into engagement with the cone of the forepart of the last. Thereafter the pad 18 is rocked downwardly to tilt the last forepart to disengage the bonding elements F, after which the post 20 is raised still higher for the purpose of sliding the last forepart upwardly to disengage the bonding elements E.

The connections between the post 20 and the slide rod 70 for raising the pad 116 into contact with the cone of the last forepart comprise a lever 118 one end of which is forked as indicated at 120 to embrace the slide rod 70 while the opposite end of the lever is pivoted at 122 to the lower extremity of the post 20. After the forepart of the last has been tilted by the downward movement of the pad 18 the post 20 is raised an additional amount to slide the forepart of the last upwardly by means comprising a lever 126 secured to a rockshaft 128 which is journaled in the bearings formed in the sides of the casing 22. The lever 126 is forked at its rear end, as shown at 130 (Fig. 7), to embrace the slide rod 70 and it is arranged to be actuated in one direction by means of a collar 132 adjustably secured to the slide rod 70 above the lever 126 and in the opposite direction by means of a collar 134 adjustably secured upon the slide rod 70 below the lever 126. The front end of the lever 126 is notched at 136 to receive the rounded rear extremity of a nipper bar or clutch 138 the forward extremity of which is received in a slot 140 formed in the side of a sleeve 142 on the post 20. The nipper bar 138 is pivoted at 144 to the sleeve 142 and is formed with an eccentric or cam face 146 adapted to be cramped against a flattened surface 148 on the post 20 by actuation of the lever 126, thereby to clutch the sleeve 142 to the post 20 so that the post 20 may be raised by the lever 126. Normally, however, the sleeve 142 is supported by means of a lever 150 in such a position that the sleeve will be unclutched from the post 20 leaving

the latter free to be raised by the lever 118 independently of the lever 126, the nipper bar 138 and the sleeve 142.

The upward movement of the post 20 for the purpose of engaging the pad 116 with the cone of the last is a movement of varying amplitude depending upon the size of the particular last which is being operated upon. Consequently, the connections for imparting this initial upward movement to the post 20 must be so constructed as to take up any over-motion of the actuating means. As shown, the lever 118 is actuated from the lever 64 through a push rod connection 152, the upper end of the push rod 152 being received in a socket in the rear arm of the lever 64, and the lower end of the push rod being received in a socket in the rear portion of the lever 118. Downward movement of the rear arm of the lever 64 is transmitted through the push rod 152 to the lever 118, rocking the lever 118 about its pivotal connection 154 with the lower end of a link 156 the upper end of which is pivoted at 158 to the lever 150. The lever 150 is pivoted at 151 and is forked at its front end, as shown at 160, the forked extremities of the lever being curved upwardly to engage lugs 162 on the sleeve 142 and thereby normally to support the sleeve 142. A spring 164 fixed at its upper end to the casing 22 and secured at its lower end to the forward portion of the lever 150 serves normally to maintain the lever in position to support the clutch sleeve 142, this position being determined by engagement of the lever with an adjustable stop screw 165. The strength of the spring 164 is sufficient to support the pivot 154 upon which the lever 118 is fulcrumed so that during the first part of the movement of the lever 64 the lever 118 will be rocked by the push rod 152 about the pivot 154 as a fixed fulcrum. The lever 118 will rock about the pivot 154 until the upward movement of the post 20 is arrested by engagement of the pad 116 with the last. Thereupon the pivotal connection 122 between the lever 118 and the post 20 becomes the fulcrum about which the lever 118 is rocked and by the action of the push rod 152, the lever 118 being swung downwardly about the fulcrum 122 sufficiently so that the link 156 will lower the lever 150 to withdraw the support of its forward portion from the clutch sleeve 142. Thereupon, the weight of the sleeve 142 becomes supported entirely by the nipper bar 138 and the lever 126, thus causing the nipper bar to grip the post 20 thus clutching the sleeve 142 to the post. The post 20 is now ready to be raised positively by the action of the lever 126 when the latter is engaged and rocked by the collar 132 on the slide rod 70.

Before the post 20 is raised as just described for the purpose of sliding the last forepart, however, the forepart of the last

must be tilted by movement of the pad 18 to disengage the bonding elements F. For this purpose, the pad 18 is supported upon a carrier 166 which is pivoted at 168 to one arm 170 of a lever mounted for rocking movement upon a rod 172 and having a downwardly extending curved arm 174 carrying a cam roll 176 at its lower extremity. A spring 178 is mounted to maintain the cam roll 176 in contact with a cam 180 fixed on a rockshaft 182 journaled in brackets carried by the casing 22. An arm 184 also fixed to the rockshaft 182 is received between upper and lower shoulders 186 (Fig. 3) formed on a sleeve 188 which is mounted with provision for sliding movement on the slide rod 70 below a collar 190 which is adjustably fixed to the upper end of the slide rod. A spring 192 secured at its lower end to a bracket on the casing 22 and at its upper end to the cam 180 normally holds the cam in the position shown in Fig. 2 and, through the arm 184, holds the sleeve 188 in engagement with the collar 190. The sleeve 188 is also normally held in the position shown in Fig. 2 by means of a latch 194 pivoted at 196 to the sleeve 188, the upper hooked end of the latch engaging a lug 200 on the collar 190. Normally, the latch is held in engagement with the pin 200 by means of a spring 202. A tail 204 on the latch is adapted to engage a fixed but adjustable abutment 206 (Fig. 2) on the casing to trip the latch for a purpose hereinafter to be explained.

As the slide rod 70 moves downwardly, the cam 180 is rocked upwardly and when the rise 210 on the cam engages the cam roll 176 the lever carrying the pad 18 is rocked in a direction to tilt the forepart of the last an amount sufficient to disengage the bonding elements F. Approximately at this time the post 20 is raised for the purpose of sliding the last forepart upwardly for the purpose of disengaging the bonding elements E. During this upward movement of the post 20 and the resulting upward sliding movement of the last forepart it is desirable to maintain the last forepart in substantially its initial tilted relation relatively to the heel part of the last. To accomplish this result, provision is made for gradually raising the pad 18 at substantially the same rate of speed as the post 20 is moved upwardly. This movement of the pad is permitted and controlled by the portion 212 of the cam 180. While the portion 55 212 of the cam 180 is operated to control the upward movement of the pad 18, the post 20 (together with the pad 116) is being raised by the lever 126 acting through the nipper bar 138, the lever 126 being actuated by the collar 132 on the slide rod 70.

As the treadle 30 approaches the lower limit of its movement the pawl 194 is tripped by engagement of the tail 204 with the abutment 206, thus disconnecting the sleeve 188 from the collar 190 so as to permit the slide

rod 70 to rise without raising the sleeve 188 and thereby actuating the cam 210 so as to apply undue pressure to the forepart of the shoe.

As a result of the positive upward movement of the post 20 and simultaneous upward movement of the pad 18 in unison with the post 20, the bonding elements E are disengaged, thus entirely disconnecting the forepart of the last from the heel part so that the last parts may be manually separated after the shoe and last have been removed from the machine. To permit removal of the shoe and last from the machine the operator releases the treadle 30 whereupon a spring 216 (Fig. 1) connected with the treadle returns the slide rod 70 to its normal elevated position and through the connections hereinbefore described with the jack pin 14 and the post 20 the jack pin is lowered to relieve the pressure between the heel part of the shoe and the abutment 16. Upon the upward movement of the slide rod 70 the collar 134 engages the forked rear extremity of the lever 126, rocking the lever in a direction to lower the sleeve 142, together with the post 20, until one of the lugs 162 on the sleeve 142 engages a lug 218 on a latch 220 the upper end of which is pivoted at 222 to the casing 22 and the lower end of which is acted upon by a spring 224 arranged to normally urge the latch 220 in a direction to move the lug 218 into the path of movement of the corresponding lug 162 on the sleeve 142. Downward movement of the sleeve 142 is thus positively arrested and inasmuch as further rocking movement of the lever 126 is prevented by engagement of the notched arm of that lever with a fixed abutment 226 (Fig. 7) the nipper bar 138 is actuated to release the sleeve 142 from the post 20 so that the post, together with the pad 116, may be returned to its normal lowered position.

When the slide rod 70 reaches its upper position the notch 104 is returned into alignment with the lock bar 100, thus permitting the lock bar to slide in a direction to release the turntable 42 to permit the shoe and last to be removed from the machine. At this time the pad 18 is exerting only a light pressure upon the forepart of the shoe. The operator then grasps the shoe and turns it to move the heel and forepart portions from beneath the abutment 16 and pad 18 respectively, and then removes the last from the jack pin. As the forepart of the shoe is swung out from beneath the pad 18 the lug 218 is rocked downwardly by the spring 192 and the pad 18 is returned to its normal position by the action of the spring 178.

When the treadle 30 is in its fully depressed position a pin 230 projecting from the front end of the lever 118, by engagement with a cam surface 232 at the lower portion of the latch 220, swings the latch upwardly a

sufficient amount to disengage the lug 218 from the lug 162 on the sleeve 142, thus enabling the nipper bar 138 to become operative to clamp the sleeve 142 to the post 5 20 as soon as the supporting lever 150 is disengaged from the sleeve.

After the shoe and last have been removed from the machine the last parts may be removed manually from the shoe and the operative parts of the machine returned into 10 normal positions adapting the machine for operation upon another last.

Having described my invention, what I claim as new and desire to secure by Letters 15 Patent of the United States is:

1. In a machine for disassembling the foreparts and heel parts of separable lasts of the type having interengaging bonding elements and means for locking said elements in interengaged relation, relatively movable members for rigidly holding one of the last parts 20 and for releasing said locking means, and means for thereafter relatively moving the last parts to disengage said bonding elements.

2. In a machine for disassembling the foreparts and heel parts of separable lasts of the type having interengaging bonding elements and means for locking said elements in interengaged relation, means including a member 30 movable heightwise of the last for holding one of the last parts and releasing said locking means, and means for thereafter relatively moving the last parts to disengage the bonding elements.

3. In a machine for disassembling the foreparts and heel parts of separable lasts of the type having interengaging bonding elements and a latch for assisting in holding the last 40 parts together, a jack pin for supporting the heel part of such a last constructed and arranged to trip the latch upon relative movement of the last and the jack pin in a direction heightwise of the last, and means for 45 thereafter relatively moving the last parts to disengage the bonding elements.

4. In a machine for disassembling the foreparts and heel parts of separable lasts of the type having interengaging bonding elements and a latch for assisting in holding the last 50 parts together, a last supporting jack pin movable to trip the latch, and means for thereafter relatively moving the last parts to disengage the bonding elements.

5. In a machine for disassembling the foreparts and heel parts of separable lasts of the type having interengaging bonding elements and a latch for assisting in holding the last 60 parts together, a jack pin for supporting the heel part of a separable last and engaging said latch, means for moving the jack pin to move the last into position to be operated upon and to release the latch, and means for 65 thereafter moving the forepart of the last

relatively to the heel part to disengage the bonding elements.

6. In a machine for disassembling the foreparts and heel parts of separable lasts of the type having interengaging bonding elements and a latch for assisting in holding the last 70 parts together, a jack pin for supporting the heel part of a separable last, a fixed abutment located above the heel part of the last, a movable abutment located above the forepart of the last, a movable post located below the forepart of the last, means for raising the jack pin to engage the heel and forepart portions of a shoe on the last with said fixed and movable abutments and for raising said post yieldingly into engagement with the forepart of the last, and means for thereafter operating said movable abutment to tilt the last forepart and for imparting a positive upward movement to said post to slide the last forepart relatively to the heel part.

7. In a machine for disassembling the foreparts and heel parts of separable lasts having interengaging bonding elements, means for clamping the heel part of a separable last, and means for moving the forepart relatively to the heel part to disengage the bonding elements.

8. In a machine for disassembling the foreparts and heel parts of separable lasts having interengaging bonding elements, means for rigidly holding a heel part of a separable last, and means for first tilting and thereafter sliding the forepart relatively to the heel part to effect disengagement of the bonding elements.

9. In a machine for disassembling the foreparts and heel parts of separable lasts having interengaging bonding elements, an abutment for engaging the heel of a shoe on a separable last, a jack pin for supporting the heel part of the last, means for moving the jack pin to engage the heel of the shoe with said abutment, a member for engaging the forepart of the shoe, and means for moving said member to move the forepart of the last relatively to the heel part to disengage the bonding elements.

10. In a machine for disassembling the foreparts and heel parts of separable lasts having interengaging bonding elements, means for rigidly holding the heel part of a separable last, movable abutment members for engaging the forepart of the last, and means for operating said abutment members to both tilt and slide the last forepart to disengage said bonding elements.

11. In a machine for disassembling the foreparts and heel parts of separable lasts having interengaging bonding elements, relatively movable abutments for engaging respectively the heel and forepart of a shoe on a separable last, a jack pin for supporting the last, means for operating the jack pin to move the shoe into engagement with said 120

abutments, and means for effecting relative movement between said abutments to disengage the bonding elements of the last.

12. In a machine for disassembling the foreparts and heel parts of separable lasts having two sets of interengaging bonding elements, means for rigidly holding a heel part of a separable last having a shoe thereon, a movable abutment engageable with the forepart of the shoe bottom, a member engageable with the cone of the forepart of the last, means for operating said member to slide the forepart relatively to the heel part to effect disengagement of one set of bonding elements, and means for operating said movable abutment to disengage the other set of bonding elements.

13. In a machine for disassembling the foreparts and heel parts of separable lasts having two sets of interengaging bonding elements, means for supporting a separable last having a shoe thereon, a member located above the forepart of the last, means for operating said member to move the last forepart in one direction to disengage one set of bonding elements, a member located below the last forepart, and means for operating said member to move the last forepart in another direction to disengage the other set of bonding elements.

14. In a machine for disassembling the foreparts and heel parts of separable lasts, a fixed abutment for engaging the heel of a shoe on a separable last, a movable abutment for engaging the forepart of the shoe, a jack pin for supporting the last and moving the shoe into engagement with said abutments, and means for operating said movable abutment to tilt the forepart of the last.

15. In a machine for disassembling the foreparts and heel parts of separable lasts, a fixed abutment for engaging the heel portion of a shoe on a separable last, an abutment for engaging the tread face of the sole at the forepart of the shoe, said abutment being pivotally mounted to adapt itself for surface engagement with the soles of shoes on lasts having different degrees of spring, means for supporting the last and moving it to engage the shoe with said abutments, and means for operating said pivotally mounted abutment to move the forepart of the last relatively to the heel part.

16. In a machine for disassembling the foreparts and heel parts of separable lasts, an abutment for engaging the heel portion of a shoe on a separable last, a movable abutment for engaging the forepart of a shoe on a separable last, a jack pin for entering a thimble hole in the heel part of the last, a carrier for the jack pin movable in a direction to engage the shoe with said abutments, the jack pin being pivotally mounted upon said carrier to permit angular adjustment of the last relatively to said abutments, and actuating mech-

anism connected with said movable abutment and with said jack pin carrier.

17. In a machine for disassembling the foreparts and heel parts of separable lasts, a jack pin for entering a thimble hole in the heel part of a separable last, the jack pin being rotatable about an axis extending heightwise of a last thereon, an abutment for engaging the heel portion of a shoe on the last, an abutment for engaging the forepart of the shoe, said abutments being arranged relatively to the jack pin to overlie the shoe bottom when the jack pin is in one position of rotary adjustment but not when the jack pin is in another position of rotary adjustment, and means for moving one of said abutments to effect relative movement between the last parts.

18. In a machine for disassembling the foreparts and heel parts of separable lasts, a jack pin for supporting a separable last, a turntable support for the jack pin rotatable about an axis parallel to the axis of the jack pin, two abutments arranged to overlie the bottom of a shoe on the last when the turntable is in one position of adjustment and to clear the bottom of the shoe when the turntable is in another position of adjustment, and a member for co-operating with the jack pin to effect relative movement of the last parts.

19. In a machine for disassembling the foreparts and heel parts of separable lasts, a jack pin for supporting a separable last, a turntable rotatable about an axis parallel to the axis of the jack pin for supporting the jack pin, two abutments arranged to overlie the bottom of a shoe on the last when the turntable is in one position of adjustment and to clear the bottom of the shoe when the turntable is in another position of adjustment, means for co-operating with the jack pin to effect relative movement of the last parts, mechanism including a slide rod for operating said means, and means constructed and arranged to lock the slide rod against movement when the turntable is in one position and to lock the turntable against movement when the slide rod is in another position.

20. In a machine for disassembling the foreparts and heel parts of separable lasts, a fixed abutment and a movable abutment relatively arranged to overlie respectively the heel and forepart of the bottom of a separable last when the last occupies a predetermined horizontal angular position, a jack pin for supporting the last in said position, said jack pin being movable about a vertical axis to enable the last to be positioned in a different horizontal angular position, a push rod normally out of vertical alignment with the jack pin, means for operating the push rod to raise the jack pin to engage a shoe on the last with said abutments, and means for mov-

ing the forepart of the last relatively to the heel part to disassemble the last parts.

21. In a machine for disassembling the foreparts and heel parts of separable lasts, abutments for engaging respectively the heel and forepart portions of a shoe on a separable last, a jack pin for supporting the last, means for yieldingly moving the jack pin to engage the shoe with said abutments, a post for engaging the cone of the forepart of the last, means for yieldingly raising the post into engagement with the last, and means for further raising the post to slide the forepart relatively to the heel part.

22. In a machine for disassembling the foreparts and heel parts of separable lasts, abutments for engaging respectively the heel and forepart portions of a shoe on a separable last, a jack pin for supporting the last, means for yieldingly moving the jack pin to engage the shoe with said abutments, a post for engaging the cone of the forepart of the last, means for yieldingly raising the post into engagement with the last, and means for positively raising the post to slide the forepart relatively to the heel part.

23. In a machine for disassembling the foreparts and heel parts of separable lasts, abutments for engaging respectively the heel and forepart portions of a shoe on a separable last, a jack pin for supporting the last, means for yieldingly moving the jack pin to engage the shoe with said abutments, a post for engaging the cone of the forepart of the last, means for yieldingly raising the post into engagement with the last, means for moving said forepart engaging abutment to tilt the last forepart, and means operating thereafter to raise said post positively to slide the last forepart relatively to the heel part.

24. In a machine for disassembling the foreparts and heel parts of separable lasts, abutments for engaging respectively the heel and forepart portions of a shoe on a separable last, a jack pin for supporting the last, means for yieldingly moving the jack pin to engage the shoe with said abutments, a post for engaging the cone of the forepart of the last, means for yieldingly raising the post into engagement with the last, means for moving said forepart engaging abutment to tilt the last forepart, means operating thereafter to raise said post positively to slide the last forepart relatively to the heel part, and means for moving said abutment during said positive movement of said post to maintain the last forepart tilted while it is being slid.

25. In a machine for disassembling the foreparts and heel parts of lasts, abutment members for engaging the heel and forepart portions of a shoe on a separable last, a jack pin for supporting the last and moving the shoe into engagement with said abutments,

a post for engaging the cone of the last, a sleeve adapted to slide on said post, a nipper bar carried by the sleeve for clutching the sleeve to the post, means including a lever for sliding the post through the sleeve to engage the post yieldingly with the last, and other means operating through said nipper bar and sleeve to raise the post positively to slide the forepart of the last relatively to the heel part.

26. In a machine for disassembling the foreparts and heel parts of separable lasts, means for supporting a separable last, a post for engaging the cone of the last, a sleeve adapted to slide on said post, a nipper bar carried by the sleeve for clutching the sleeve to the post, means normally effective for supporting said sleeve to render said nipper bar inoperative, means for sliding the post through the sleeve to engage the post with said last, means for withdrawing said support to render the nipper bar operative to clamp the sleeve to the post, and means co-operating with said nipper bar positively to raise the post to slide the forepart of the last relatively to the heel part.

27. In a machine for disassembling the foreparts and heel parts of separable lasts, means for supporting a separable last, a slideable post for moving the forepart of the last, a sleeve slidably mounted on said post, a nipper bar carried by the sleeve for clutching the sleeve to the post, a yielding member normally supporting said sleeve to render said nipper bar ineffective, a treadle, means operative upon depression of the treadle for sliding the post through the sleeve to engage the post with the last and for withdrawing said yielding support to render the nipper bar operative to clamp the sleeve to the post, means co-operating with the nipper bar positively to raise the sleeve and post to move the last forepart and thereafter to lower said sleeve and post, and a normally inoperative latch movable upon depression of the treadle into position to arrest positively the downward movement of the sleeve to disengage the nipper bar from the post upon subsequent release of the treadle.

28. In a machine for disassembling the foreparts and heel parts of separable lasts, means for supporting a separable last, a slideable post for moving the forepart of the last, a sleeve slideable mounted on said post, a nipper bar carried by the sleeve for clutching the sleeve to the post, a yielding member normally supporting said sleeve to render said nipper bar ineffective, a treadle, means operative upon depression of the treadle for sliding the post through the sleeve to engage the post with the last and for withdrawing said yielding support to render the nipper bar operative to clamp the sleeve to the post, means co-operating with the nipper bar positively to raise the sleeve and post

to move the last forepart and thereafter to lower said sleeve and post, a latch for positively arresting the downward movement of the sleeve to disengage the nipper bar from the post, and means operative when the treadle is in released position to disengage the latch from the sleeve.

29. In a machine for disassembling the foreparts and heel parts of separable lasts, means for supporting one of the parts of a separable last, means for effecting relative tilting movements between the last parts to position them in a predetermined angular relation one to the other, and means for thereafter effecting relative sliding movements between the last parts to separate them, the means for effecting said relative tilting movements being operable during said relative sliding movements of the last parts to maintain said predetermined angular relation of the last parts.

30. In a machine for disassembling the foreparts and heel parts of separable lasts, means for supporting the heel part of a separable last, means for tilting the forepart of the last to position it in a predetermined angular relation to the heel part, and means for thereafter sliding the forepart to separate it from the heel part, the means for tilting the forepart being operable during the sliding of the forepart to maintain said predetermined angular relation of the forepart to the heel part.

31. In a machine for disassembling the foreparts and heel parts of separable lasts, means for rigidly supporting the heel part of a separable last having a shoe thereon, means engageable with the cone of the forepart of the last for sliding the forepart to separate it from the heel part, a member for engaging the tread face of the sole of the shoe, and means for operating said member to tilt the forepart before it is slid relatively to the heel part and thereafter to maintain the forepart substantially in the same tilted relation to the heel part throughout said sliding movement.

32. In a machine for disassembling the foreparts and heel parts of separable lasts, means for rigidly supporting the heel part of a separable last having a shoe thereon, means engageable with the cone of the forepart of the last for sliding the forepart to separate it from the heel part, a member for engaging the tread face of the sole of the shoe, and means for moving said member in one direction to tilt the forepart of the last prior to said sliding movement and to move said member in another direction during the continuance of said sliding movement to maintain the last forepart in substantially the same tilted relation to the heel part while the forepart is being slid.

33. In a machine for disassembling the foreparts and heel parts of separable lasts

having shoes thereon, a fixed abutment for engaging the tread face of the heel of a shoe on a separable last, a jack pin for supporting the last, means for moving the jack pin to engage the heel of the shoe with said abutment rigidly to support the heel part of the last, and means for tilting and sliding the forepart of the last to separate it from the heel part.

34. In a machine for disassembling the foreparts and heel parts of separable lasts having interengaging bonding elements including a latch releasable from within a thimble hole in the heel part of the last, a jack pin for entering the thimble hole, means on the jack pin for engaging said latch, means for moving the jack pin relatively to the heel part of the last to trip said latch, and means for moving the forepart of the last relatively to the heel part to separate said last parts.

35. In a machine for disassembling the foreparts and heel parts of separable lasts having shoes thereon and having interengageable bonding elements for holding the foreparts and heel parts together, a fixed abutment for engaging the heel of a shoe on such a last, a movable member for engaging the forepart of the sole of the shoe, a jack pin for supporting the heel part of the last, the jack pin being movable in a direction to engage the shoe with the abutment and with said member and being pivoted at one end for tilting adjustment about an axis transverse to its length to adapt shoes of different shapes and sizes to be engaged both with said abutment and with said member by movement of said jack pin and means for moving said member to disengage said bonding elements.

36. In a machine for disassembling the foreparts and heel parts of separable lasts of the type having interengaging bonding elements adapted to be disengaged by relative tilting and sliding movements of the last parts, a jack pin for supporting the heel part of such a last, a member for engaging the forepart of the last, means for sliding the forepart relatively to the heel part, and means for moving said member in one direction to tilt the forepart of the last before it is slid and for thereafter moving said member in the opposite direction at substantially the same rate of speed as that at which the last forepart is slid to maintain said last forepart tilted while it is being slid.

37. In a machine for disassembling the foreparts and heel parts of separable lasts having interengaging bonding elements and a pivoted hook latch for assisting in holding the last parts together, means for supporting the heel part of the last and tripping the latch, and means for relatively moving the last parts to disengage the bonding elements.

38. In a machine for disassembling the foreparts and heel parts of separable lasts having interengaging bonding elements and

a latch for assisting in holding the last parts together, a member engageable with the latch for supporting the last, an abutment for engaging the shoe on the last, means for actuating said member to move the shoe into engagement with said abutment and to trip said latch, and other means for relatively moving the last parts to disengage the bonding elements.

39. In a machine for disassembling the forepart and heel parts of separable lasts having interengaging bonding elements and a latch for assisting in holding the last parts together, a jack pin for entering a thimble hole in the heel part of a separable last, a projection on the jack pin for supporting the last by engagement with the latch, means for moving the jack pin to trip the latch, and means for moving the forepart of the last relatively to the heel part to disengage the bonding elements.

40. In a machine of the class described, in combination, a fixed abutment, a jack pin for co-operating with said abutment to support a last, an actuator, a lever adapted to be rocked by the actuator for moving the jack pin, a spring constraining the lever to rock about a fixed fulcrum and thereafter to yield to permit overmotion of the actuator, and means operated by the overmotion of the actuator for moving the last forepart.

41. In a machine of the class described, a movable jack pin for engaging the heel part of a separable last, a member for tilting the forepart of the last, a member for sliding the forepart of the last, means for yieldingly moving the jack pin and said second member into operative positions, and means for thereafter moving the first member to tilt the last forepart and for later moving said second member to slide the last forepart.

42. In a machine of the class described, a movable jack pin for supporting a last, an actuator, a lever connected with the jack pin and with said actuator for moving the jack pin into operative position, means constraining said lever to rock about a fixed fulcrum during said movement of the jack pin and to yield to permit overmotion of the actuator, and means operated by the overmotion of the actuator for relatively moving the last parts.

43. In a machine of the class described, a fixed abutment, a movable jack pin for co-operating with said abutment to support lasts of different sizes, a movable abutment engageable with the foreparts of lasts of different sizes to move the foreparts relatively to the heel parts, a treadle-operated slide rod, a sleeve on the slide rod, a clutch operable to connect the sleeve to the slide rod throughout a portion only of the movement of the slide rod and thereafter to disconnect the sleeve from the rod, means actuated by said sleeve for yieldingly moving the jack pin into operative position and for yieldingly

positioning said movable abutment in engagement with the forepart of the last, and means operated by the slide rod after the sleeve has been disconnected therefrom for unyieldingly moving said movable abutment 70 to tilt the forepart of the last relatively to the heel part.

44. In a machine of the class described, a fixed abutment, a movable jack pin for co-operating with said abutment to support lasts 75 of different sizes, a movable abutment engageable with the foreparts of lasts of different sizes to move the foreparts relatively to the heel parts, a treadle-operated slide rod, a sleeve on the slide rod, a clutch operable to connect the sleeve to the slide rod throughout a portion only of the movement of the slide rod and thereafter to disconnect the sleeve from the rod, means actuated by said sleeve for yieldingly moving the jack pin into 80 operative position and for yieldingly positioning said movable abutment in engagement with the forepart of the last, means actuated by the slide rod after the sleeve has been disconnected therefrom for unyieldingly 85 moving said movable abutment to move the forepart of the last relatively to the heel part, and means operated through the connections with said slide rod for imparting a preliminary 90 tilting movement to the last forepart. 95

45. In a machine of the class described, in combination, a jack pin for supporting a separable last, a fixed abutment and a movable abutment arranged respectively above the heel part and forepart of the last on the 100 jack pin and adapted to co-operate with the jack pin in supporting the last, a movable post adapted to engage the cone of the forepart, a treadle-operated slide rod, means including a lever connecting the slide rod with the jack pin for yieldingly moving the jack pin into operative position, a second lever connected with said post for moving the latter yieldingly into engagement with the last, 105 connections between the first lever and the second lever for operating the latter, a sleeve on said post, a clutch for securing the sleeve to the post, a third lever normally positioned to support said sleeve so as to maintain said clutch inoperative, connections between the second lever and the third lever for moving the latter to withdraw its support from said sleeve, and a fourth lever connected with said slide rod and with said clutch for positively moving said post to slide the forepart 110 of the last. 115

46. In a machine of the class described, in combination, a jack pin and means co-operating therewith for clamping a separable last, 120 a movable post adapted to engage the cone of the forepart of the last, a treadle-operated slide rod, means including a lever connecting the slide rod with the jack pin for yieldingly moving the jack pin into clamping position, a second lever connected with said 125 130

post for moving the latter yieldingly into engagement with the last, connections between the first lever and the second lever for operating the latter, a sleeve on said post, a clutch for securing the sleeve to the post, a third lever normally positioned to support said sleeve so as to maintain said clutch inoperative, connections between the second lever and the third lever for moving the latter to withdraw its support from said sleeve, a fourth lever connected with said slide rod and with said clutch for positively moving said post to slide the forepart of the last, and means connected with said slide rod for operating said movable abutment to tilt the forepart of the last prior to said sliding movement.

47. In a machine for disassembling the foreparts and heel parts of separable lasts, means for supporting a separable last, a movable abutment engageable with the forepart of the last, means for sliding the forepart upwardly relatively to the heel part, a treadle, an actuator movable in one direction upon depression of the treadle and in another direction upon release of the treadle, connections between said actuator and said abutment including a cam operable upon depression of the treadle first to lower said abutment to tilt the last forepart downwardly prior to said upward sliding movement thereof and later to raise said abutment in unison with the upward sliding movement of the last forepart, and means for disconnecting said cam from said actuator.

In testimony whereof I have signed my name to this specification.

LAURENCE E. TOPHAM.
